UNITED STATES PATENT OFFICE.

ALVAH F. LENT, OF NEWARK, NEW JERSEY, ASSIGNOR TO CHARLES F. PAULUS, OF NEWARK, NEW JERSEY.

CAP-EXPLODING DEVICE.

976,814.

Specification of Letters Patent. Patented Nov. 22, 1910.

Application filed January 25, 1910. Serial No. 539,976.

To all whom it may concern:

Be it known that I, ALVAH F. LENT, a citizen of the United States of America, and a resident of Newark, county of Essex, and 5 State of New Jersey, have invented a certain new and useful Cap-Exploding Device, of which the following is a specification.

My invention relates to devices for exploding paper percussion caps and the like, 10 and comprises a simple and inexpensive device for the purpose, which is easily operated and which may be operated without liability of injury to the user.

The object of my invention is to produce 15 a simple and inexpensive device of the character referred to which is easily operated and which may be operated without injury to the user.

I will now proceed to describe my invention with reference to the accompanying 20 drawing, in which one form of the device embodying my invention is illustrated.

In said drawing: Figure 1 shows a side view of the device; Fig. 2 a perspective elevation thereof; Fig. 3 a perspective elevation of the anvil or cap-holding piece, slightly tilted; and Fig. 4 a perspective elevation of the hammer or striking piece, also slightly tilted.

30 In the drawing 1 designates a holder and guide, which in the form shown is a rectangular wooden stick, 2 designates the anvil and cap-holding device which is mounted upon the stick 1, usually and preferably 35 near the end thereof; and 3 designates a sliding hammer or striker arranged to slide back and forth upon the stick 1. This hammer is arranged to be retracted against the action of a suitable spring and to be drawn 40 forward by such spring; and as a spring for this purpose, I employ an ordinary elastic rubber band 4, which at one end passes over a nail 5 (which nail also serves to hold the anvil 2 in place) said rubber band at its 45 other end passing over a projection 6 on the rear of the hammer 3.

The anvil 2 is provided with a dovetailed recess 7 on the face adjacent the hammer 3, to receive the cap to be exploded; 50 and in Figs. 1 and 2 8 designates such a cap. The hammer 3 has a boss 9 adapted to enter said recess, and in the face of this boss there is a shallow groove 10 serving as a vent for the explosion gases at the instant when the 55 cap explodes. The anvil 2 has an angular

rearward extension 11 provided with openings 12 and 13 for the passage of the stick 1, and with cross bars 14, 15 and 16, of which 14 and 16 are arranged to be on one side of the stick, and 15 is arranged to be 60 on the other side thereof. The hammer 3 is provided with a similar angular rearward extension 17, provided with apertures 18 and 19, and with cross bars 20, 21 and 22 of which 20 and 22 are arranged to be on the 65 upper side of the stick and 21 on the under side thereof. It will be seen that the forms of the hammer and anvil are such that these parts are readily cast in large numbers in multiple molds (that is to say, a large 70 number of these devices may be cast simultaneously in molds contained within the same molding flask and gated to be poured at the same time. This is a common and well known method of producing simple 75 cast articles such as these, in large quantities and requires no special description.)

In using the cap exploding device, the stick is held by the end opposite that on which the anvil 2 is mounted, and the hammer is drawn back, usually by the thumb of the operator; and a cap having been placed in the anvil, the hammer is released and allowed to be drawn forward by the rubber band, striking the cap held by the 85 anvil and so causing the explosion thereof.

The construction of the device is such that the hand of the operator is at a considerable distance from the cap when the latter explodes, so that there is for that reason 90 very little liability of particles of the cap or the explosive composition thereof, flying back and burning the hand of the operator; also the construction of the parts is such that the fragments of the cap and of 95 the ash from the explosive charge, tend to fly upward rather than backward, the hammer 3 serving effectually as a shield to prevent these particles from flying backward.

What I claim is:—

1. A device such as described, comprising a guide, an anvil having a base portion secured to the guide, and an actuating portion extending upwardly from the guide, a hammer having a base portion mounted to 105 slide on said guide, and an upright actuating portion, and an elastic band connecting said hammer to a fixed portion of the device and tending normally to draw the hammer toward the anvil, said anvil having in its 110

- upright actuating portion a cap-holding recess and the hammer having a portion adapted to enter said recess to strike against a cap held therein.
- 5 2. A device such as described, comprising a guide, and a hammer and an anvil mounted thereon, said hammer and anvil each comprising an upright actuating portion and rearwardly extending supporting portion, the latter having two apertures in line with one another for the passage of the guide.
- 10 3. A device such as described, comprising a guide, and a hammer and an anvil mounted thereon, said hammer and anvil each
- 15 comprising an upright actuating portion and rearwardly extending supporting portion, the latter having two apertures in line with one another for the passage of the guide.

comprising an upright actuating portion and rearwardly extending supporting portion, the latter having two apertures in line with one another for the passage of the guide, such rearwardly extending portion 20 comprising cross pieces on opposite sides of the guide.

In testimony whereof I have signed this specification in the presence of two subscribing witnesses.

ALVAH F. LENT.
